UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

LINE-SPACING MECHANISM FOR TYPEWRITERS.

Application filed July 17, 1920. Serial No. 396,889.

To all whom it may concern:

Be it known that I, OTTO A. HOKANSON, a citizen of the United States, residing at Woodstock, in the county of McHenry and State of Illinois, have invented certain new and useful Improvements in Line-Spacing Mechanism for Typewriters, of which the following is a specification.

This invention relates to typewriters, and more particularly to that portion of typewriter mechanism by which the paper is shifted to bring a new line into printing position, and has for its object the provision of mechanism of the class named which shall be of improved construction and operation.

The invention is exemplified in the combination and arrangement of parts shown in the drawing and described in the following specification, and it is more particularly pointed out in the appended claims.

In the drawing—

Fig. 1 is a top plan view of a portion of a typewriter having one embodiment of the present invention applied thereto; and

Fig. 2 is a section taken substantially on line 2—2 of Fig. 1.

Although this invention is applicable to various forms of typewriters, it is shown by way of illustration as applied to a typewriter having a foldable platen carriage frame 10 mounted on arms 11 which are pivotally connected at 12 to the base or main frame 13 of the typewriter. A platen carriage 14 is mounted to travel on the carriage frame 10 and is provided with end plates 15 between which a platen 16 is journaled. A ratchet wheel 17 is secured to the platen 16 and is provided with a spring detent 18 having a roller 19 arranged to engage the teeth of the ratchet wheel 17 to cause the platen when rotated to move in steps corresponding to the line spacing of the typewritten page. The detent 18 is adjustably mounted on the end plate 15 of the platen carriage by means of a screw 20 and a pin 21 which engage a slot 22 formed in a flange 23 on the detent 18. The detent may be adjusted in the direction of its length to regulate its position relative to the ratchet wheel 17 and normally the detent resiliently forces the roller 19 into engagement with the teeth of the ratchet wheel. An arm 24 is pivotally mounted at 25 on the plate 15 and is provided with a

pin 26 projecting through a slot 27 in the plate 15 into position to engage the upper face of the detent 18. A crank 28 is connected with the arm 24 and is provided with a handle 29, by means of which the pin 26 may be shifted in the slot 27 to hold the detent out of engagement with the ratchet wheel 17, leaving the platen free to be rotated independently of the control of the detent. A spring arm 30 is connected with the detent 18 and forms a brake strap arranged to engage a brake disc 31 connected with a platen spindle 32. When the detent 18 is forced away from the ratchet wheel 17 the brake spring 30 will be caused to bear against the brake disc 31 to hold the platen from moving too freely in its bearings and to retain the platen in any position of adjustment to which it may be turned by the operator.

The left-hand end plate of the platen carriage 15 is provided with a bracket 33 having a line space lever 34 pivoted at 35 thereon. The lever 34 is provided with a finger-piece 36 by which the platen carriage is moved along the carriage frame when it is desired to begin a new line of writing. The pressure for moving the carriage swings the lever 34 upon its pivot and operates the line-spacing mechanism for rotating the platen. This mechanism includes a member 37 pivotally mounted at 38 on the arm 39 of the lever 34 and having a pawl 40 on the forward end thereof in position to engage the teeth of the ratchet wheel 17. The member 37 is provided with a downwardly extending tail-piece 41 which is connected by a spring 42 to a lug 43 bent downwardly from the arm 39 of the lever 34. Sufficient play is allowed in the pivotal connection 38 between the lever arm 39 and the member 37 to permit the pawl 40 to move into and out of contact with the ratchet wheel 17 and the spring 42 normally tends to hold the pawl in position to engage the teeth of the ratchet wheel.

A finger lever 44 is pivotally mounted at 45 on the plate 15 and is provided with a pin 46 which extends beneath the member 37 to hold the pawl 40 out of engagement with the ratchet teeth when the pawl 40 is in its forward position. The member 37 is offset, however, as shown at 47, so that when the lever 34 is moved in a counterclockwise direction, as viewed in Fig. 1, for shifting the platen carriage the member 37 will be

retracted until the offset portion moves past the pin 46, thus permitting the pawl 40 to engage the ratchet teeth and shift the platen one or two spaces, depending upon 5 the position of the pin 46. When the pin 46 is in the position shown in full lines in Fig. 2 the pawl 40 will be permitted to engage the ratchet teeth near the beginning of the movement of the lever 34, and thus 10 the platen will be shifted two spaces. If the lever 44 is moved downwardly to bring the pin 46 into the broken line position shown in Fig. 2, the pawl 40 will be held out of engagement with the ratchet wheel 15 during a portion of its movement and will engage the teeth of the ratchet wheel in time to impart a single space movement to the platen. The lever 44 may be shifted 20 by means of a handle 48 projecting through a slot 49 in the plate 15 and is held in its two positions of adjustment by a knob 50 formed on the end of the lever and arranged to engage depressions 51 in the plate 15. A similar knob and depressions may be 25 provided for holding the lever 28 in its adjusted positions. A bracket 52 is bent laterally from the upper edge of the plate 15 and is provided with a downwardly bent flange 53 having a slot therein for guiding 30 the member 37. This slot retains the member 37 in proper alinement at all times, but permits longitudinal movement thereof for rotating the wheel 17, and also allows vertical movement to bring the pawl into and 35 out of engagement with the ratchet teeth. A spring 55 is also connected with the flange 53 and with the lug 43 on the lever arm 39 to restore the lever 34 and the member 37 to their original positions when the lever 40 is released. The bracket 52 is provided 40 on its forward face with a notch 56 for engaging a lug 57 on the member 37, thus forming a positive stop for limiting the movement of the member 37 and the lever 34 so that the platen will not be rotated more 45 than the desired amount. When the lug 57 is in contact with the notch 56, the shoulder 58 at the base of the lug 57 will underlie the bracket 52 holding the member 37 against upward movement so that the pawl 40 cannot rise out of the notches in the ratchet wheel 17. This provides a positive 50 lock for the platen during the return of the carriage. It will be seen that the parts 55 are so designed that they can practically all be made of sheet metal stampings and that when assembled they form a simple and compact line-spacing device.

60 I claim:—

1. Line spacing mechanism for a typewriter comprising a horizontally swinging lever, a bar supported directly on said lever, a supplemental support for said bar, said bar having an offset in the portion thereof engaging said supplemental support to shift

the height of said bar when moved by said lever, a ratchet engaging member carried by said bar, and means for shifting said supplemental support to vary the action of said ratchet engaging member. 70

2. The combination with the platen, platen carriage and ratchet wheel of a typewriter, of line spacing mechanism for said platen comprising a horizontally swinging lever pivoted on said carriage in the rear of said platen, a bar supported at its rear end by said lever and having a toothed member thereon for engaging said ratchet wheel, a supplemental support for said bar upon which said bar is moved by said lever, said support being arranged to hold said toothed member out of engagement with said ratchet wheel during a portion of the movement of said member and to permit engagement of said member and wheel during another portion of said movement, and means for shifting said support to vary the operation of said toothed member. 75 80 85

3. In combination, a platen carriage having a rotatable platen thereon, a ratchet wheel secured to said platen, a bell crank lever pivoted on said carriage in the rear of said platen to swing in a horizontal plane, a bar supported by one arm of said bell crank lever and extending forwardly therefrom, a supplemental support for said bar, said bar being supported entirely by said arm and said supplemental support and having an offset portion therein cooperating with said supplemental support to raise the said bar to different heights for different positions thereof, a tooth on said bar for engaging said ratchet wheel, and means for adjusting said supplemental support to vary the period or engagement between said tooth and wheel. 90 95 100 105

4. In combination, a platen carriage, a rotatable platen mounted on said carriage, a ratchet wheel secured to said platen, a horizontally swinging bell crank lever on said carriage, an elongated bar having an arm thereon bent at right angles thereto and pivotally connected with one arm of said bell crank lever, a support for said bar, a tail-piece on said bar having a spring connected therewith for holding said bar against said support, a tooth on said bar for engaging said ratchet wheel, said bar having an offset therein for permitting movement of said tooth into engagement with said ratchet wheel during a portion of the movement of said bar, means for adjusting said support to vary the period of engagement between said tooth and ratchet wheel, a guide for said bar, and a stop on said bar for engaging said guide to limit the movement of said bar and consequently the movement of said bell crank lever. 110 115 120 125

5. In combination, a platen carriage having a rotatable platen thereon, a ratchet

wheel secured to said platen, a detent having a roller for engaging the teeth of said ratchet wheel, a brake for said platen connected with said detent, means for shifting 5 said brake and detent to cause said brake and detent alternatively to cooperate with said platen, and means for adjustably connecting said detent with said carriage to permit movement of said detent for varying 10 the angular positions at which said platen is held.

6. In combination, a platen carriage, a rotatable platen thereon, a ratchet wheel secured to said platen, a horizontally swing- 15 ing lever arm, a pawl supported directly on

said lever arm, a supplemental support for said pawl for controlling the period of engagement between said pawl and ratchet, a detent for engaging said ratchet wheel, a 20 brake connected with said detent and arranged to cooperate with said platen when said detent is out of engagement with said ratchet wheel, and means for adjusting said detent to vary the position at which said ratchet wheel is held thereby. 25

In testimony whereof I have signed my name to this specification on this 21st day of June, A. D. 1920.

OTTO A. HOKANSON.
